[57] CLAIM

The ornamental design for a ski rack for an automobile
or the like, as shown and described.

DESCRIPTION

FIG. 1 is a top perspective view of a ski rack for an
automobile or the like showing my new design.

FIG. 2 is a right side elevational view thereof, the left
side being a mirror image thereof.

FIG. 3 is a top plan view thereof.

FIG. 4 is a bottom plan view thereof.

FIG. 5 is an elevational view of one end thereof, the
opposite end being a mirror image thereof.
